(57) **CLAIM**

An ornamental design for a portable display stand for students, as shown and described.

DESCRIPTION

FIG. 1 is a top plan view of a portable display stand for students showing my new design.

FIG. 2 is a front elevation view of FIG. 1.

FIG. 3 is a left-side elevation view of FIG. 1.

FIG. 4 is a right-side elevation view of FIG. 1.

FIG. 5 is a back elevation view of FIG. 1.

FIG. 6 is a bottom plan view of FIG. 1.

FIG. 7 is a front perspective view of the portable display stand for students; and,

FIG. 8 is a front perspective view showing the portable display stand for students in use.

The broken lines shown in FIG. 8 depict environmental subject matter that forms no part of the claimed design.
